UNITED STATES PATENT OFFICE.

HENRY F. STARBUCK, OF CHICAGO, ILLINOIS, ASSIGNOR TO WILLIAM A. REYNOLDS, OF SAME PLACE.

COLD-AIR MACHINE.

SPECIFICATION forming part of Letters Patent No. 255,895, dated April 4, 1882.

Application filed October 25, 1880. (No model.)

To all whom it may concern:

Be it known that I, HENRY F. STARBUCK, residing at Chicago, in the county of Cook and State of Illinois, and a citizen of the United States, have invented a new and useful Improvement in Cold-Air Machines, of which the following is a full description, reference being had to the accompanying drawings, in which—

Figure 1 is a front elevation of the front of the case partially broken away, and the upper or expansion and the lower or compression cylinders on one side with their respective plungers or pistons and the upper and lower receiving and discharging valves in section, the driving wheel or pulley being also in section, the section being taken on line $x\ x$ of Fig. 16; Fig. 2, a horizontal section on line $y\ y$ of Fig. 15, with the plungers or pistons and the air-induction tube for the lower valve removed; Fig. 3, a vertical section on line $z\ z$ of Fig. 15, the air-induction tube for the lower valve being in elevation; Fig. 4, a detail, being an elevation of the lower valve, its casing or chamber, and air-induction tube, with a portion of the lower air-chamber in section; Fig. 5, a detail, being a central vertical section through the lower valve, its casing or chamber, and air-induction tube, showing the valve open, with a portion of the lower air-chamber in section; Fig. 6, a detail, being a central vertical section through the lower valve, its casings, or chamber, and air-induction tube, showing the valve closed, with a portion of the lower air-chamber in section; Fig. 7, a transverse section through the valve and its casing; Fig. 8, a transverse section through the valve and its casing, showing the valve in the position it occupies in Fig. 5; Fig. 9, a transverse section with the valve in the position shown in Fig. 6, the valve being shown respectively in these three figures partially open, fully open, and completely closed; Fig. 10, a detail, being a central vertical section of the casing or chamber for the upper valve; Fig. 11, a detail, being a horizontal section through the upper valve and its casing, taken on a line with the center of the upper ports of Fig. 10, showing the valve open for the discharge of air from the upper air-chamber; Fig. 12, a detail, being a central vertical section, at right angles

to that shown in Fig. 10, of the upper valve and its casing or chamber, showing the valve in the position shown in Fig. 11; Figs. 13 and 14, details, being horizontal sections of the valve in the same plane as that of Fig. 11, showing respectively the positions of the valve in relation to the induction and eduction ports at the beginning and end of the shut-off of the induction-port from the upper air-chamber, the ports being shown in outline; Fig. 15, a front elevation; Fig. 16, a side elevation; Fig. 17, a perspective view. Figs. 3 and 16 show the crank-shaft and the devices connected therewith for operating the plungers or pistons and the rotary valves in a reverse position from the position in which such parts are shown in Figs. 1 and 17. Figs. 4 to 14, inclusive, are enlarged.

This invention relates to machines which are primarily designed for the purpose of producing a current of cold air to act as a refrigerant or for cooling purposes, and it may be used for any purpose where it is desired to produce a cooling or lowering of the temperature; and it relates more particularly to the construction and arrangement of the upper and lower air-chambers and upper or expansion cylinders, and lower or compression cylinders and valves coacting with such cylinders, and devices for operating the valves in their several relations to each other to produce the required expansion and contraction by which the air is cooled under pressure, as hereinafter more specifically described; and it has for its objects to improve the construction, arrangement, and operation of the cylinders, and increase the utility and reliability of the apparatus for producing the desired result; to improve the method by which air is drawn into the apparatus and ejected therefrom in a cooled condition to act as a refrigerant; to improve the construction, arrangement, and operation of the devices by which the air is drawn into the machine and ejected therefrom in their relation to each other, and to the receiving and discharging cylinders and the air chambers; and to improve generally the construction, arrangement, and operation of the several devices constituting the machine in their several relations to each other, whereby their combined action will be more

positive, uniform, and reliable in accomplishing the desired end, the machine as a whole being designed for use in the manufacture of ice, as well as for general refrigeration; and its 5 nature consists in providing a main reservoir composed of an upper and lower section or chamber connected by pipes, and combining with the chambers of such reservoir, valves, and valve-chambers of peculiar construction, 10 as hereinafter more specifically described; in providing one of the chambers with an induction-pipe formed of a hollow cylinder carrying one of the valves through which the air is conducted to the chamber coacting with such 15 valve; in the peculiar and novel construction of the valve and its chamber; in the peculiar and novel construction and arrangement of the valve-chamber and receiving-chamber or reservoir in their relation to each other; in providing a driving-shaft and actuating-gear for giving the valves a rotary movement, the driving-shaft having cranks thereon for operating the plungers or pistons of the cylinders; in the 20 peculiar and novel construction and arrangement of the cylinders in relation to the receiving-chambers, valves, and valve-casings, whereby a continuous action is produced; and in the several parts and combinations of parts, hereinafter more specifically pointed out and 25 claimed as new.

In the drawings, A represents the compression-cylinders; A', the expanding-cylinders; B and B', rotary valves, differing slightly in the 30 construction and arrangement of their ports; C, the reservoir; C', the connecting-pipes; D, the plungers or pistons of the cylinders A; E, the piston-heads or plungers of the cylinders A'; F, the pitmen or rods for the plungers D; F', the pitmen or rods for the pistons E; G, the 35 double-crank shaft for operating the pitmen or rods; H, the chamber or tank for the reception of water; I, the space around the cylinders A', forming an insulated cooling-chamber and snow-box; J, the tube or hollow shaft through 40 which air is admitted to the cylinders A; K, the valve-stem of the valve B'; a, the beveled-gear wheel on the shaft G; b and b', beveled-gear wheels on the ends of the stems for the 45 valves B and B', respectively; c, the cranks on the shaft G; d, the actuating-heads on the 50 ends of the pitmen or connecting-rods for the plungers or piston-heads; e, the springs around the valve-stems for keeping the valves in place; f, the inlet-ports from the reservoir C 55 through the casing of the valve B'; g, the chambers in the valve B'; h, the inlet-ports through the chamber or casing of the valve B'; i, the cut-off ring for the valve; j, the pin for attaching the ring i; j', the opening for the attaching- 60 pin of the ring i; k, the set-screw for holding the ring in position when adjusted; l, the exhaust-ports from the chamber or casing of the valve B'; m, the exhaust-ports in the chamber or casing of the valve B', leading to the cylinders; n, the chambers or passages in the valve B', coacting with the ports m; o, the in-

let-port in the valve B; o', the inlet-port through the casing of the valve B, leading to the cylinders; p, the exhaust-port through the valve B; p', the exhaust-port through the casing of the valve B; q, the seat of the valve B; r, the check-valve; r', the opening into the chamber C.

The compression-cylinders A and the expanding-cylinders A' are single acting, and are, as shown, arranged in pairs, the compression-cylinders being above or on a higher plane than the expanding-cylinders, and in the same vertical plane as the expanding-cylinders. These cylinders A and A' are of corresponding size and proportions, and their dimensions will 70 depend upon the size of the machine and the capacity which it is desired the machine shall have. As shown, each compressing-cylinder has working therein a plunger or piston, D, having a body the length of which is somewhat greater than the working-length of the cylinder, the diameter of the body corresponding with the interior diameter of the cylinder, and the interior of the body having an opening or chamber into which the rod or pitman 80 by which it is operated passes, so as to be connected with the bottom of the piston or plunger; but some other form of plunger or piston which will do the required work can be used.

As shown, each upper or expanding cylinder 85 has working therein an ordinary piston head or disk, E, which may be of any of the usual and well-known forms, and this piston head or disk is operated by a pitman or connecting rod, to the end of which it is secured 90 in any suitable manner.

As shown, the pistons or plungers D and E are operated from the shaft G, which shaft is mounted in suitable bearings located on the side of the outer casing of the machine, and is 95 driven from a pulley-wheel on one end or in any other suitable manner. This shaft G has thereon two cranks, e, one of which is located in line with each cylinder or pair of cylinders A A', and to these cranks is connected in any 100 suitable manner a sliding block located so as to reciprocate back and forth in the end of a head, d, formed with or attached to the rods or pitmen F F', a head, d, being provided for each pitman, and the block to which the head 105 is connected sliding back and forth, so that by a revolution of the shaft G the crank will alternately advance and recede the pistons or plungers D E, and these cranks are so arranged in relation to each other as to stand 110 in opposite directions, so that when one crank is in position to withdraw the head or disk E and advance the plunger or piston D on one side the opposite crank will be in position to raise or withdraw the piston D and advance 115 the head or disk E, by which arrangement it will be seen that when the pistons or plungers on one side are operating in one direction the pistons or plungers on the opposite side are operating in the reverse direction, keeping up 120 a continuous inflow and outflow of air through the cylinders.

The valve B has an exterior of a conical shape, and is provided with interior passages, one of which leads from the top of the valve to the side thereof and the other from the bottom of the valve to the opposite side thereof. These passages form the ports through the valve for the induction and exduction of the air to and from the cylinders, according to the position in which they are brought in relation to the ports for each cylinder by the rotation of the valve, the passage *o* forming the inlet-port and the passage *p* the exhaust-port. This valve is located in a casing having an opening corresponding in shape to the exterior shape of the valve, through the sides of which casing or chamber are openings *o'* and *p'*, which form ports for admission of air to either one of the cylinders A, or for the exhaustion of the air from such cylinders, accordingly as the ports *o* and *p* are brought in line therewith. This casing or chamber for the valve is located and arranged in such manner in relation to the cylinders as that communication is had with one cylinder through the port *o'* and with the other cylinder through the port *p'* at such point in relation to the plungers or pistons D as that air will be admitted to the respective cylinders when the plunger thereof is elevated or raised.

Air is admitted to the cylinders through the tube or hollow shaft J, to the lower end of which the valve B is attached in any suitable manner, so as to bring the opening *o*, which leads to the top of the valve, in line with the opening through the tube or shaft J, the air entering at the top of the tube or shaft and passing down through the same into the opening *o*, out through the port *o'* or *p'*, accordingly as the valve is turned into one or the other of the cylinders A.

To the upper end of the tube or shaft J is connected in any suitable manner, so as to leave openings for the admission of the air, a stem or rod, to the upper end of which is connected or attached a beveled-gear wheel, *b*, so that the hollow shaft and the continuation thereof by the rod or stem form the stems for the valve. The wheel *b* meshes with a beveled-gear wheel, *a*, located on a shaft, G, and by means of these beveled-gear wheels *a* *b* the valve B is given its rotation, so as to bring its ports or passages *o* *p* alternately in position to act with the passages or ports *o'* *p'*.

As shown in Figs. 1 and 2, the casing for the valve B has side extensions to fit against the side of the cylinders A, and each cylinder, at the lower end thereof, in line with the ports *o'* *p'*, is provided with an opening by means of which communication is formed between the ports and the interior of the cylinders; but this communication might be made in some other suitable manner in case the exterior casing or chamber for the valve is not formed to fit the cylinders or the cylinders do not come in contact therewith. The upper valve, B', is also conical or of a taper shape on its exterior, but differs somewhat in the construction of its

passages or ports from the construction of the valve B.

The valve B' is provided with four chambers, *g* *n*, two on each side of the valve and one above the other, the chambers on each side being directly opposite and in line with each other, and the two sets of chambers, upper and lower, being separated one from the other by a division or partition plate, as shown in Fig. 12, the upper chamber, *g*, forming passages for the admission of air, and the lower chambers, *n*, passages through which air is exhausted. The casing which receives this valve B' has a conical central opening corresponding in shape to the shape of the valve, and its exterior is formed in any suitable manner, so as to be attached within the chamber or reservoir for compressed air. The interior of this casing or chamber for the valve B' is provided with passages *h*, with which the passages or chambers *g* coincide as the valve is rotated, and these passages *h* open into ports *m*, which ports are located so as to be in line with the chambers *n*, and communicate therewith as the valve rotates, the chambers *n* also communicating with an exhaust-port, *o*, also formed in the casing or chamber for the valve B'.

The ports *m* are located in line with each other on opposite sides of the casing or chamber, and the exhaust-port *o* is located in the same plane with the ports *m* on one side of the chamber or casing, and stands at right angles in relation to the ports *m*. The chamber or casing of this valve is also provided with the ports *f*, leading to the compressed-air chamber or reservoir C, and each port *f* is located in line with the passages *h*, which passages are formed on opposite sides of the interior of the chamber or casing, the ports *f* being located at right angles to such passages on each side of the chamber or casing adjacent to the reservoir or chamber C. The ports *m* communicate with the cylinders A' through suitable openings formed in the cylinders, or in any other suitable manner, the port on one side communicating with one cylinder and the port on the other side communicating with the opposite cylinder, and, if desired, the exterior of the casing or chamber for the valve B' may be formed so as to fit against the side of each cylinder, the same as shown for the casing for the valve B in Figs. 1 and 2, in which case the cylinders A' are provided with openings coinciding with the ports *m*, and forming a communication between the ports and cylinders, as shown in Fig. 1. This valve B is located on a stem, K, passing up through the cooling-chamber and the snow-box I, to the opposite end of which stem is attached a beveled-gear wheel, *b'*, which meshes with the beveled-gear wheel *a*, by means of which wheels *a* *b'* the valve B' is rotated so as to bring the chambers *g* *n* and passages *h* in line with the ports *f*, *n*, and *o*, as required, for the admission of air from the cooling-chamber and its passage into and out from the cylinders A' alternately.

The location of the ports o p of the valve B in relation to the ports o' p' of its chamber or casing is shown in Figs. 5 and 6, and the construction and arrangement of the valve 5 and its seat and their relation to the chamber C and communication therewith are also shown in the same figures.

The form of construction and arrangement of the valve B' and its casing or chamber is shown in Figs. 10, 11, and 12, and these same figures also show the location and arrangement of the receiving-chambers g , discharging-chambers n , passages or openings h , and ports m f o in their several relations to each 15 other.

The reservoir or chamber C for compressed air may be formed, as shown, with an upper and lower compartment connected by the pipe c' , or in some other suitable form. In the 20 upper compartment and around the cylinders A' is formed a chamber, I, which chamber is insulated from the cylinders and chamber or reservoir C, so as to form a cooling-chamber and snow-box, and this chamber is so arranged 25 in relation to the cylinders that the cold air delivered by or through the valve B' forms a medium for cooling the chamber and keeping it cool, so as to retain any snow which may be formed therein, thereby utilizing the cold arising 30 from the snow and assisting to that extent in maintaining a low temperature in the expanding-cylinders A', which cylinders are located within the receptacle or chamber I.

The chamber H is located in the lower portion 35 of the reservoir or main chamber around the cylinders A, and extends upward around the pipes C', and into this chamber cold water is admitted in any suitable manner, so as to fill the lower portion thereof around the compressing-cylinders A, which water, after entering the chamber, is made to pass out at or near the top in any suitable manner. This chamber, when filled with flowing water, as described, keeps the cylinders A A and valve 40 B cool, the valve and cylinders being located 45 within the chamber, and the water also forms a means for cooling the pipes C' and a portion of the main reservoir or air-chamber C, so as to keep the parts which are in contact 50 with the water at a lower temperature, which aids in cooling the current of air and maintaining the cylinders and valve in a cool condition, and thereby increasing the action of the cylinders in the operation of the machine 55 by abstracting a portion of the latent heat of the air produced by the operation, so that it will be delivered to the expansion-cylinders in a cooler condition than otherwise would be the case if the water-chamber H were not used.

The valve B', as shown, is provided with an 60 adjustable cut-off formed by a movable ring, i , held in position by means of a pin, j , and set-screw a . This ring encircles the lower part of the valve, and by means of the set-screw and 65 pin can be so adjusted as to admit the proper quantity of air into the expansion-cylinders by

turning it in the proper direction to increase or decrease the amount of opening g , so that the admission of air to the port f will be cut off sooner or later in the rotation of the valve. 70 This ring or cut-off is not shown in Fig. 1, and can be made adjustable and held in position by other means than the pin j and the set-screw k , the pin, as shown, having a square shank or body and entering a corresponding -shaped 75 opening, j' , formed therefor in the body of the valve. Any other form of cut-off than that shown and described may be used, if so desired, that will do the work.

As shown, air is admitted into the chamber 80 C from the port p through an opening or port, r' , formed in the seat q of the valve, which seat is secured in any suitable manner to the body or upper part of the chamber C, and, as shown, a check-valve, r , which may be of any of the 85 ordinary and well-known forms of construction, is provided for controlling the admission of air into the chamber C; but this check-valve is not a necessity, and may be omitted, if desired.

As shown, the machine stands in a vertical 90 or upright position; but it can be arranged to operate in a horizontal position, if so desired.

The valve B controls the passage of air into the cylinders A A and from such cylinders into the lower portion of the main reservoir or 95 chamber C, such control of the air by the valve B being through its rotation and arrangement of its ports or passages o p in relation to the ports or passages o' p' in its chamber or casing leading to the cylinders. The valve B' controls 100 the passage of air from the main reservoir or receiver into the expansion-cylinders, and from such cylinders through the exhaust-port to the place desired, such control of the air by the valve B' being through its rotation and the arrangement of its chambers g and n in relation to the inlet-port f , air-passages h , ports m , leading to 105 the cylinders, and exhaust-port o leading to the place of discharge, in their several relations to each other and to the cylinders A', in 110 which the air is expanded.

As shown, the valves are maintained in position so as to revolve freely and not become misplaced by means of coil-springs e , located 115 around their respective stems, one end of the spring resting upon the beveled wheel by which the valve is rotated, and the other acting against a collar or ring formed on the shaft, so as to force the valve into this opening and hold it therein; but other forms of devices or 120 means can be used for this purpose.

In operation air is admitted through the pipe J from the exterior, and passing down such pipe enters the opening or passage o in the valve B, and through this passage o air will pass to 125 the cylinders A alternately, accordingly as the passage or opening o coincides with the port o' or p' , the air entering each cylinder at the time that the piston or plunger D for such cylinder commences its upward stroke, or during such upward stroke, and before it reaches 130 the highest point of ascent and commences to

descend. As the piston or plunger D commences to descend the valve B will have rotated so as to bring the opening or passage *p* in the valve B in communication with the port 5 of the cylinder the piston of which is descending, and the piston will force the air from the cylinder through the port and the passage or opening *p* and the passage or opening *r* into the chamber C, the air passing through the 10 check-valve, when such valve is used, as usual. At the same time that the plunger or piston of one cylinder A begins to descend the plunger or piston of the other cylinder A will commence to ascend, at which time the opening 15 or passage *o* by the rotation of the valve is brought into communication with the port communicating with such cylinder in which the piston or plunger has commenced its ascent, and air will pass through the pipe J and 20 opening or passage *o* and the port of the cylinder into the cylinder below the piston or plunger, charging that cylinder with the air, which air will be discharged therefrom on the descent of the piston or plunger, the valve by 25 its rotation having brought its opening or passage *p* into communication with the port leading to the cylinder, the rotation of the valve also bringing the passage *o* into communication with the other cylinder, from which the 30 air has been discharged, recharging such cylinder. By this arrangement it will be seen that while one cylinder A is being discharged the other cylinder is being charged, and this discharging and charging of the cylinders is 35 alternate, each half-revolution of the valve bringing the openings or passages *o* and *p* into communication with the ports *o'* and *p'*, so as to charge and discharge the cylinders.

The operation of the valve B' is similar to 40 that of the valve B in charging and discharging the cylinders A'. Air is admitted from the main reservoir or chamber C through a port, *f*, and passes through such port into a chamber, *g*, which is in communication therewith, from 45 which chamber it passes through the opening *h* as the valve rotates into the port *m*, and from thence into the expansion-cylinder with which this port communicates, the piston head or disk of such cylinder, as the air enters, having commenced its ascent or being on its upward stroke. At the same time the piston head or disk of the other cylinder A' has commenced its descent or is on its downward stroke, and the air in such cylinder will be 50 forced out through the port *m*, which communicates therewith, into the chamber *n*, from which chamber it passes, as the valve rotates, through the exhaust-port *o* to the place where it is to be distributed or used; the chamber *n* being brought into communication with the port *m* to discharge the air as the chamber *n* on the opposite side is brought into communication with the opposite port, *m*, for the air to enter and charge the cylinder which is being 55 filled as the air is being discharged from its neighboring cylinder.

It will be understood that a single inlet-port, *f*, is to be provided, located in line with and standing transversely at right angles to the chambers or passages *h* and passing through 70 the valve casing or chamber to the reservoir or chamber C; and it will also be understood that a single outlet-port, *o*, is to be provided, located transverse or at right angles to and in line with the ports *m*, so that as the valve 75 B' is rotated the air will pass alternately through the port *f* into each chamber *n*, and through the passages *h* and port *m* to the cylinders, and the air from the cylinders will be discharged through the ports *m*, chambers *n*, 80 and exhaust-port *o*, the arrangement being such that when air is entering one cylinder the other one is closed and remains so until a chamber, *n*, is brought in communication therewith by the rotation of the valve, and 85 at the same time that one port, *f*, is open for the admission of air to one cylinder through the passage *h* and port *m* air will be discharged from the other cylinder through the port *m*, chamber *n*, and port *o*. By this arrangement 90 it will be seen that while one cylinder is being charged the other is being discharged, and as the valve rotates the cylinder which is being discharged will be charged, while the other cylinder which was being charged will be discharged, this charging and discharging of the cylinder being alternate and occurring with each rotation of the valve B' through the arrangement of the ports and passages just described. 100

The chamber or casing for the valve may have a side expansion or wing so formed as to project or extend over the end of the cylinder on the respective sides of the casing or chamber and form the cover for closing the cylinder, such extension being provided with a suitable passage or opening leading from the port into the cylinder on each side, so as to form a means of communication for charging and discharging the cylinders. 105 110

By means of these rotary valves B and B', with their ports and the ports leading to the cylinders, and by the arrangement and mode of operation of the plungers or pistons, it will be seen that air is admitted into one cylinder 115 while being discharged from the other cylinder, accordingly as the valve is in position for the induction or exhalation of the air, so that with each half-revolution of the crank-shaft one cylinder is being charged and the other discharged. The air which is forced into the chambers C through the compressing-cylinders A passes from the chamber into which it enters through the pipe C' into the other chamber, from which chamber it is drawn through 125 the action of the expanding-cylinders A', keeping up a continuous movement or circulation through the chambers and cylinders, which circulation is maintained by the action of the cylinders and the valve which coacts therewith. 130

As shown, the cylinders A and the pistons or plungers D, which work therein, are kept

lubricated by the water in the chamber H, the cylinders having small openings leading to the interior, and the plungers each having small grooves, which coact with such openings and 5 allow water to enter in sufficient quantity to act as a lubricant, and also to pack the pistons or plungers and prevent leaking. The valve B is also kept lubricated in the same manner from the water in the chamber H, and any 10 small quantity of water which may find its way through the joints of either the plungers or the valve will be collected in the reservoir C, and can be removed through an automatic jet-cock suitably arranged for the purpose or by any 15 other suitable means.

The particular form of machine shown and described is especially adapted to be used on shipboard, where beef and other perishable freight is stored for transportation; but it 20 can be used in other places and for other purposes, and its form may be easily modified to adapt it to other uses, the arrangement of the cylinders in relation to the valve by which they are supplied with air, and by which air is 25 exhausted in the manner hereinbefore described, remaining the same when the other parts of the machine are modified.

Other forms of reservoir or receiving-chambers C than the one shown and described can 30 be used so long as such reservoir or chamber is adapted to receive the cylinders and valves and operate in conjunction therewith.

What I claim as new, and desire to secure by Letters Patent, is—

35 1. A main receiving-chamber or reservoir for compressed air, in combination with compressing-cylinders A and rotary valve B, having its body provided with ports o p, and located in a casing or chamber provided with 40 ports o' p', leading to the cylinders for alternately charging and discharging the cylinders, substantially as specified.

2. A main receiving-chamber or reservoir for compressed air, in combination with expanding-cylinders A' and a rotary valve having 45 its body provided with chambers g n, and located in a casing or chamber provided with passages h, ports m, inlet-port f, and exhaust-port o for supplying air to the cylinders and 50 withdrawing it therefrom, substantially as and for the purposes specified.

3. A main receiving-chamber or reservoir for compressed air, in combination with compressing-cylinders A, rotary valve B, having 55 ports or openings o p, and located in a casing or chamber having ports o' p' leading to the compressing-cylinders, and discharge-port r, expanding-cylinders A', and rotary valve B', having chambers g n, and located in a casing 60 or chamber provided with inlet-port f and outlet port o, and with openings or passages h and ports m leading to the expanding-cylinders.

ders for forcing air into the receiving-chamber or reservoir and withdrawing it therefrom, substantially as specified.

65

4. The air-supply pipe J, and rotary valve B, having openings or ports o p through its body, and located in a casing or chamber having ports o' p', in combination with the compressing-cylinders A and a main receiving-chamber 70 or reservoir for supplying air under pressure to the chamber or reservoir, substantially as specified.

5. A rotary valve for supplying air, having its body provided with openings or ports o and 75 p, leading respectively from the top of the valve to the side thereof and from the bottom of the valve to the side thereof, in combination with a casing or chamber adapted to receive the valve, and having ports o' p', in communication with which the ports o p are alternately brought by the rotation of the valve, and receiving and discharging cylinders communicating with the chamber or casing through the ports o' p' for supplying air to one cylinder 80 while the other is being discharged, substantially as specified.

6. A rotary valve, B', having on opposite sides of its exterior chambers g n, located one above the other, in combination with a 90 casing or chamber adapted to receive the valve, and having inlet-port f, which communicates with the chambers g, air passages or openings h, receiving and discharging ports m, and exhaust-port o, communicating with the chambers n, and expanding-cylinders communicating with the chamber or casing through the ports m for supplying air to the cylinders and discharging it therefrom, substantially as specified.

95

7. In a refrigerating-machine, the combination of two compression-cylinders, A, rotary valve B, having ports o p, and located in a chamber or casing having ports o' p' leading to the cylinders, with a compressed-air reservoir or 105 chamber, C, connecting-pipes C', and cooling-tanks H for supplying air to the cylinders and educting it therefrom, and keeping the cylinders and valve cool and at the proper temperature for use, substantially as specified.

100

8. In a refrigerating-machine, the combination of two expanding-cylinders, A', and a valve, B', constructed as described, and located in a chamber or casing formed as described, with a cooling-chamber in which the cylinders 115 are located, and a main receiving-chamber or reservoir for compressed air for keeping the cylinders and valve cool and forming a cooling-chamber and ice-box, substantially as and for the purposes specified.
